A. Hayward,

Inventor

Daniel Armstrong

DANIEL ARMSTRONG, OF CHICAGO, ILLINOIS.

Letters Patent No. 83,439, dated October 27, 1868.

IMPROVEMENT IN SASH-FASTENER.

The Schedule referred to in these Letters Patent and making part of the same.

To all whom it may concern:

Be it known that I, DANIEL ARMSTRONG, of Chicago, in the county of Cook, in the State of Illinois, have invented an Improved Sash-Fastener; and I do hereby declare that the following is a full and exact description thereof, reference being had to the accompanying drawings, and to the letters of reference marked thereon, making a part of this specification, in which—

Figure 1 is a longitudinal elevation of my invention, as applied to a sash.

This invention relates to an improvement on that class of fasteners which are placed parallel with the lower rail of the sash, and have a double bolt with rubber in its ends, for holding the sash in position; and its nature, in part, consists in the use of a central thimble or socket, which supports the inner ends of tubular bolts, and also a coil-spring. The latter passing into the ends of the bolts, is made to operate both of them at the same time, and hold the sash in place.

To enable others skilled in the art to make and use my invention, I have marked corresponding parts with similar letters, and will now give a detailed description.

H represents the lower rail of a sash, and I the frame in which it runs. The bolts of the fastener, shown at A A', are made of metal pipe, of suitable size and strength, and have metal heads or partitions, h h, rigidly attached to their inner sides, and at suitable distances from the ends, to permit rubber plugs, F F, to be inserted in the usual manner. And pins d d are put through the bolts, at suitable distances from their inner ends, and used as supports for a coil-spring, m, to bear against. This construction will be clearly seen by reference to the sectional drawing of bolt A'.

B represents a metal thimble, which is made large enough for the inner ends of the bolts to slide in, and it has lugs at the bottom and top, through which screws

c c are put, to hold it to the sash, the upper lug terminating in a lifter, E, for raising the sash in the usual manner. The outer ends of the bolts are held in position by means of thimbles G G, made large enough for the bolts to slide in, and are fastened to the sash in the same manner as the thimble B. Thumb-pieces O O are attached to the bolts A A', at such distances from their inner ends as is convenient for grasping them by the thumb and finger, and moving the bolts from the sash-frame.

I know that the application of a double bolt for fastening sash is not new, neither is the rubber F in the end. I therefore limit the scope of my improvement to the peculiar construction of the bolts, and the novel manner in which they are operated, not claiming to have originated an entirely new fastener. The difference, however, between this device and others used for a like purpose, is very obvious, inasmuch as the bolts A A' are hollow, with a single spring inside, and consequently require no casing to conceal any of the working parts. And as to cheapness, my fastener can be made at less than one-half of the cost of similar inventions, which are as durable and convenient.

Having thus described my invention,

What I claim, and desire to secure by Letters Patent of the United States, is—

The arrangement of the thimble B and coil-spring m, the latter fitting into the ends of the bolts A A', and operating both of them at the same time, in combination with thimbles G G, pins d d, and thumb-pieces c c, as and for the purpose set forth:

DANIEL ARMSTRONG,
